UNITED STATES PATENT OFFICE.

WILLARD IRVING TWOMBLY, OF NEW YORK, N. Y.

SAFETY-HARNESS FOR AVIATORS.

1,050,874.

Specification of Letters Patent. Patented Jan. 21, 1913.

Application filed December 18, 1911. Serial No. 666,616.

To all whom it may concern:

Be it known that I, WILLARD IRVING TWOMBLY, a citizen of the United States, residing in the borough of Manhattan, in the city, county, and State of New York, have invented new and useful Improvements in Safety-Harness for Aviators, of which the following is a specification.

This invention relates to harness for aviators. In order to prevent the aviator from being jounced from the seat in the aeroplane when alighting and from other causes the aviator is securely held in position in the seat by straps suitably fixed to the aeroplane and passed around the body of the aviator, and the aviator can only be released by the undoing of buckles or the like which is a slow operation. In many aeroplane accidents could the aviator have quickly released himself such accidents would not necessarily have been fatal, as it would have given the aviator an opportunity to get clear of the aeroplane by jumping prior to the aeroplane coming to the ground should the accident be due to the falling of the same, and while he would be injured it would prevent him from being pinned and smashed in the wreckage of the aeroplane.

It is the object of the present invention to provide a safety harness for aviators that will at all times firmly and yieldingly maintain the aviator in position in the aeroplane, but which is so constructed that it may be quickly and readily releasable to permit the aviator to clear himself of the aeroplane in case of accident, and for this purpose I provide braces consisting of a series of straps to engage about the body of the aviator yieldingly connected to the framework of the aeroplane at the back of the aviator with the free ends so assembled in front of the aviator that by a simple manipulation they are quickly and simultaneously released.

In the drawing accompanying and forming part of the specification, Figure 1 is a perspective view of a portion of the framework of the fuselage of an aeroplane showing in full lines my improved harness applied to an aviator, and in dotted lines substantially the positions to which the straps will be thrown when released. Fig. 2 is a front elevation of my improved aviator's harness; and Fig. 3 is a sectional detail view taken on the line X—X of Fig. 2, looking in the direction of the arrows, and showing one

manner of releasably assembling the free ends of the straps in front of the aviator.

Similar characters of reference designate like parts throughout the different views of the drawing.

In the embodiment of my invention illustrated in the drawing I have shown the same as braces comprising straps 4, 4 to extend over the shoulders and straps 5, 5 to extend around the body of the aviator, said straps preferably connected in pairs, that is, one of the shoulder and one of the body straps, to rings 6, 6 in the rear of the aviator. The rings 6 preferably consist of two coils, the one strap as 5, connected to one coil and the other strap 4 connected to the other coil, so that the straps will be clamped between the coils of the ring and prevent undue movement of the straps and the rings relatively to each other. The shoulder straps of each pair are adjustable, for which purpose they consist of two sections connected by a buckle 7 secured to one of the sections. The shoulder straps are also preferably adjustably connected in the rear of the aviator as by means of a sectional strap 8 connected by a suitable buckle. The straps are so assembled and locked in position in front of the aviator as to be quickly and readily released, and for this purpose each of the shoulder straps and one of the body straps are provided with chapes 8 having an orifice whereby they are assembled upon a stud 9 forming a part of or fixed to a plate 13 secured to the free end of one of the body straps 5. The straps are maintained in assembled position by a key, such as a split or cotter pin 10, passing transversely through the stud 9, said pin always maintained in connection with one of the straps 5 by a chain 11 connected to an eye 12 fixed to the plate 13. The chapes 8 are so assembled on the stud 9 that when the key 10 is removed they will be thrown off from the said stud, and for this purpose I provide a suitable spring, in the present instance shown as a leaf spring 14 fixed at one end to the plate 13, said spring having an opening near its free end through which the stud passes and so tensioned that the free end will normally assume a position near the outer end of the stud, as shown in dotted lines in Fig. 3, thereby tending to always throw the chapes off from the stud.

The harness is secured to the framework 119

15 of the fuselage of an aeroplane, preferably to one of the standards, by means of straps 16 connected at one end to the rings 6 the other end passes around one of the 5 standards of the framework, and secured by a suitable buckle, as clearly shown in Fig. 1. It is essential that the harness when secured to the framework by the straps 16 not only maintain the aviator in position but also 10 permit him to have a limited free movement, for which purpose the straps 16 are made up of two sections yieldingly connected by members 17 which may consist of a rubber loop or other elastic material. To 15 prevent undue stretching of the members 17 with a consequent liability of the breakage of the same, and also to prevent separation of the strap sections should said members 17 be broken I provide auxiliary connecting 20 members 18 which may consist of strong loops of cable of suitable flexible material. It is to be understood that the cable loops are larger than the yielding loops, as clearly shown in Fig. 2.

25 In practice the harness is first secured to the framework 15 by the straps 16, the aviator then taking his place in the seat in the aeroplane when the straps 4 are placed over the shoulders and the straps 5 around the 30 body below the arms and the free ends assembled on the stud 9 carried by one of the straps. As the straps are assembled on the stud they are pressed down against the tension of the spring 14 and locked in assembled position by the key 10, the key being springy or resilient is frictionally locked in position in the stud with no liability of the accidental release of the same. Should it be 35 found that the body straps are located too high or too low around the body the shoulder straps are let out or taken up as may be desired, and should the shoulder straps lie too close to the neck, or hang over the shoulders they may be adjusted to occupy 40 the proper position by taking up or letting out the strap sections 8'. In order to quickly release the straps it is only necessary to pull out the key 10, which can be readily 45 done by grasping the chain 11, the pressure 50 on the spring 14 then being released the tension of the spring will throw the straps off from the stud to substantially the positions shown in dotted lines in Fig. 1, the harness falling clear of the aviator.

55 Variations may be resorted to within the scope of my invention.

Having thus described my invention, I claim:

1. A safety harness for aviators, comprising a series of straps connected together at one end whereby the harness is adapted to be connected to the framework of an aeroplane, said straps adapted to extend over the shoulders and around the body; and means 60 connected to the free ends of said straps to

assemble all of the free ends of the straps in front of the aviator to permit of the simultaneous release of the same, substantially as and for the purpose specified.

2. A safety harness for aviators, comprising a plurality of straps connected together at one end and adapted to extend over the shoulders and around the body, means carried by the free ends of one of the straps upon which the free ends of the other straps are adapted to be assembled; quick releasable means to releasably maintain the straps in assembled position; and means to simultaneously release all of said straps when the retaining means is removed, substantially as and for the purpose specified. 70

3. A safety harness for aviators, comprising straps connected together at one end and adapted to extend around the body; means carried by the free end of one of the straps 75 upon which the free ends of the other straps are assembled in front of the aviator; quick removable means to retain the free ends of the straps in assembled position; means connected to one of the straps to simultaneously release all of the straps when the retaining means is removed; and means to connect the harness to an aeroplane, substantially as and for the purpose specified. 80

4. A safety harness for aviators, comprising straps to extend over the shoulders and around the body of the aviator and connected at one end to the framework of an aeroplane; a stud carried at the free end of one of said straps on which the free ends 95 of the other straps are assembled to releasably connect all of said ends of the straps; means to lock said ends of the straps on the stud; and means to simultaneously throw all of the straps off of the stud when the locking means is released, substantially as and for the purpose specified. 100

5. A safety harness for aviators comprising a plurality of straps to be connected at one end to the framework of an aeroplane 110 and adapted to extend over the shoulders and around the body of the aviator; a stud carried at the free end of one of said straps on which the free ends of the other straps are assembled to releasably connect said ends; a removable pin passing transversely 115 through said stud to maintain the straps assembled on said stud; and a spring fixed to the stud-carrying strap, the tension of said spring tending to throw the straps off of the stud when the pin is removed, substantially as and for the purpose specified. 120

6. A safety harness for aviators, comprising straps connected at one end to the framework of an aeroplane and adapted to 125 extend around the body of the aviator; chapes fixed to the free ends of said straps; a stud fixed to one of said chapes to project laterally therefrom and upon which stud the other chapes are assembled to releas- 130

ably connect the free ends of the straps; a cotter pin passing transversely through said stud to maintain the chapes assembled thereon; and a spring connected to the stud-car-
5 ryng chape tensioned to throw the chapes from the stud when the pin is removed to release the straps, substantially as and for the purpose specified.

7. A safety harness for aviators, comprising a plurality of straps yieldingly connected at one end to the framework, said straps to extend over the shoulders and around the body of the aviator; a chape having a laterally projecting stud fixed to the free end of 15 one of the straps; a leaf spring also connected to said chape having a perforation through which the stud passes, the outer end of the spring normally in a position near the end of the stud; chapes fixed to 20 the free ends of the other straps having openings in which the stud is adapted to engage to assemble the ends of the straps, a removable pin passing transversely through the stud to releasably maintain the chapes 25 in assembled position on the stud against the tension of the spring; said spring simultaneously throwing off all of the straps from the stud when the pin is removed, substantially as and for the purpose specified.

8. A safety harness for aviators, comprising two pairs of straps, one strap of each pair extending over the shoulders, and the other strap of each pair extending around the body, of the aviator; a pair of rings the 35 ends of each pair of straps connected to one of said rings and whereby the harness is connected to the framework of an aeroplane; and means to releasably connect the other ends of the straps in front of the aviator, substantially as and for the purpose specified.

40 9. A safety harness for aviators, comprising two pairs of straps, one strap of each pair adjustable and extending over the

shoulders, and the other strap of each pair 45 extending around the body, of the aviator; a ring connected to the ends of each pair of straps in back of the aviator; a strap to adjustably connect the shoulder straps of each pair in back of the aviator; means connect- 50 ed to the rings to yieldingly connect the harness to the framework of an aeroplane; and means to releasably connect the other ends of said straps in front of the aviator, substantially as and for the purpose specified. 55

10. A safety harness for aviators, comprising straps to extend around the body of the aviator; rings connected to one end of said straps; means to releasably connect the other ends of said straps in front of the 60 aviator; and means to yieldingly connect the harness to the framework of an aeroplane, comprising sectional straps one section connected to one of the rings and the other section to the framework, and a resil- 65 ent member to connect the strap sections, substantially as and for the purpose specified.

11. A safety harness for aviators, comprising straps to extend around the body of the aviator; rings connected to one end of 70 said straps; means to releasably connect the other ends of said straps in front of the aviator; and means to adjustably and yieldingly connect the harness to the framework of an aeroplane, comprising sectional straps, 75 one section connected to the rings and the other section to the framework, and a rubber band and flexible cable of greater length than the rubber band to connect the strap sections, said cable preventing undue 80 stretching of the rubber band and the separation of the strap sections by the accidental breakage of said band.
